UNITED STATES PATENT OFFICE.

IRA D. HURLBUT, OF PRAIRIE DU CHIEN, WISCONSIN.

STEREOTYPING CASTING-BOX.

SPECIFICATION forming part of Letters Patent No. 376,743, dated January 24, 1888.

Application filed January 3, 1887. Serial No. 223,326. (No model.)

To all whom it may concern:

Be it known that I, IRA D. HURLBUT, a citizen of the United States, residing at Prairie du Chien, in the county of Crawford and State of Wisconsin, have invented certain new and useful Improvements in Stereotyping Casting-Boxes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in stereotyping casting-boxes which are adjusted on a frame of suitable height, so as to be used in a horizontal, vertical, or inclined position, and have adjustable bearers, the transverse 20 one of which is held in place by reversible lugs which can be changed for various sized matrices.

The objects of my invention are to provide an easily-operated, strong, and durable casting-box for various-sized work and secure against leakage. I attain these objects by the mechanism illustrated in the accompanying drawings, in which—

Figure 1 is a perspective view of the entire 30 machine. Fig. 2 is a top view of the bottom of the casting-box, the bearers B B and B', place of the matrix C, and lugs D D. Fig. 3 is a view of the corner of the bottom of the casting-box, the end of the transverse bearer 35 B', the lug D, and cap-screw d'.

Similar letters refer to similar parts throughout the several views.

The lugs are all L-shaped, of metal, and each one has a slot in its longer L for the thumb-screw d', which is screwed into the side of the 40 bottom of the casting-box between the middle of the side and its end. The shoulder of the thumb-screw, when tightened, holds the lug in any desired place, and the short L supports the bearer B'. The lug may be moved backward or forward the length of the slot, and may be reversed to give it greater reaching power to hold the bearer B' at any place between the center and the end of the casting-box, as may be desired.

45 To operate the machine, place the transverse bearer B' to the line of the end of the matrix and adjust the lugs D D, so as to keep it in position, place the bearers B B to the lines of the sides of the matrix, with one end of each 50 against the transverse bearer, put a sheet of heavy Manila paper over all, and then set on the top H and fasten it down firmly with the screw G, elevate the open end of the casting-box, and it is ready to pour the molten metal 55 into it.

What I claim as my invention, and desire to secure by Letters Patent, relates to the lugs, and is—

In stereotyping machines, the combination 60 of the casting-box with two adjustable and reversible lugs, substantially as herein described, and for the uses and purposes herein set forth.

In testimony whereof I affix my signature in presence of two witnesses.

IRA D. HURLBUT.
